[57] CLAIM

The ornamental design for a reel seat for fishing rod, as shown and described.

DESCRIPTION

FIG. 1 is a perspective view of the top, front and left sides of a reel seat for fishing rod according to the present invention.

FIG. 2 is a perspective view of the bottom, front and left sides of the reel seat for fishing rod as shown in FIG. 1.

FIG. 3 is a perspective view of the bottom, rear and left sides of the reel seat for fishing rod as shown in FIG. 1.

FIG. 4 is a top plan view of the reel seat for fishing rod as shown in FIG. 1.

FIG. 5 is a bottom plan view of the reel seat for fishing rod as shown in FIG. 1.

FIG. 6 is a front elevational view of the reel seat for fishing rod as shown in FIG. 1.

FIG. 7 is a right side elevational view of the reel seat for fishing rod as shown in FIG. 1.

FIG. 8 is a rear elevational view of the reel seat for fishing rod as shown in FIG. 1.

FIG. 9 is a left side elevational view of the reel seat for fishing rod as shown in FIG. 1.
